CLAIM

The ornamental design for a two-rail mount for electronic display, as shown and described.

DESCRIPTION

FIG. 1 is a front perspective view of a two-rail mount for electronic display according to the invention;

FIG. 2 is a front elevation view of the two-rail mount for electronic display depicted in FIG. 1;

FIG. 3 is a rear elevation view of the two-rail mount for electronic display depicted in FIG. 1;

FIG. 4 is a side elevation view of the two-rail mount for electronic display depicted in FIG. 1;

FIG. 5 is an opposing side elevation view of the two-rail mount for electronic display depicted in FIG. 1;

FIG. 6 is a top plan view of the two-rail mount for electronic display depicted in FIG. 1; and,

FIG. 7 is a bottom plan view of the two-rail mount for electronic display depicted in FIG. 1.
